CONSOLE FOR THE SALE OF TRAVEL INSURANCE

Irvin M. Lemon, Redondo Beach, Calif., assignor to Mutual of Omaha Insurance Company

Filed Oct. 31, 1972, Ser. No. 302,556

Term of patent 14 years

Int. Cl. D6—06

U.S. Cl. D6—181

FIG.1

FIG.5

FIG. 1 is a front perspective view of a console for the sale of travel insurance showing my new design;

FIG. 2 is a left side elevational view;

FIG. 3 is a front elevational view;

FIG. 4 is a rear elevational view; and

FIG. 5 is a top plan view.

I claim:

The ornamental design for a console for the sale of travel insurance, substantially as shown.
